UNITED STATES PATENT OFFICE.

JACOB ZIMMERMAN, OF PHILADELPHIA, PENNSYLVANIA, ASSIGNOR TO PARAMOUNT KNITTING MILLS, OF PHILADELPHIA, PENNSYLVANIA, A CORPORATION OF PENNSYLVANIA.

SWEATER.

Application filed April 29, 1927. Serial No. 187,620.

The present invention is concerned with improvements in knitted garments, and finds one of its preferred embodiments in an improved sweater of the sport coat type.

5 The so-called knitted sport coats present a somewhat tailored appearance when worn, but have a tendency to lose their shape due to the inherent stretchability of the knitted body-forming fabric. Usually after the 10 sweaters have been worn for a short length of time, this tendency of the fabric to stretch becomes patent, particularly across the shoulder portions of the garment, with the result that the shoulders sag and the upper 15 end of the garment sleeves, instead of being disposed in proper position, assume a position well below the wearer's shoulders. In consequence, the garment has an ill-fitting and unattractive appearance.

20 The greatest strains on the garment also occur at the shoulder lines due to the transverse stresses on the body along these lines with the result that the front and rear sections of the sweater tend to split or separate 25 along the shoulder lines, and the sweater body also frequently breaks away from the sleeves and from the finishing band at this point.

In accordance with the present invention, 30 I have provided a garment so reinforced that the shoulder portions are substantially proof against sagging, and the life of the garment is materially prolonged due to the fact that the danger of separation of any of the garment seams adjacent the shoulder is completely eliminated.

There have been previous attempts to reinforce the shoulders by concealed lines of reinforcing tape following the shoulder lines 40 of the garment. Such means has been altogether ineffective because the threads connecting the inelastic tape to the elastic body have been quickly broken when transverse stretching strains occur across the shoulder 45 lines of the garment.

In accordance with the present invention, I employ a sag-resisting, reinforcing piece of knitted fabric limiting the transverse stretch of the garment shoulders, and connecting the two shoulder line seams of the garment. This reinforcing member is sufficiently elastic to yield under ordinary stretching strains, but has sufficient strength

to oppose dangerous stretching of the garment across the shoulder line. In consequence, the garment is retained in shape and there is no danger of separation of the connected parts of the garment along or adjacent the shoulder seams.

Other and more general objects of the invention are to provide a garment of neat and attractive appearance, well suited to the requirements of economical manufacture, and of rugged, durable construction.

With the above noted and other objects in view, the invention consists in certain novel features of construction and combinations and arrangements of parts, as will be more fully hereinafter set forth and pointed out in the claim. The invention may be more fully understood from the following description in connection with the accompanying drawings, wherein—

Fig. 1 is a perspective view showing a garment embodying the present invention in applied position.

Fig. 2 is a perspective view of the inside of the garment showing the position of the improved reinforcing means.

Fig. 3 is an enlarged diagrammatic sectional view on the line 3—3 of Fig. 2.

In the drawings I have shown a sweater of the so-called sport coat type including a body formed of an integral back section 10 and front section 11. A lower marginal 85 finishing strip 12 of conventional character is employed, and a single finishing strip 13 follows the side edges of the body and the upper edges thereof in the usual manner. If desired, the front and rear sections of the 90 body may be integral along the shoulder lines 14 or may be connected by a suitable line of stitching. These shoulder lines extend from the armhole portions 15 of the body to the intermediate portion of the band 95 13, the inner ends of the shoulder lines being spaced well apart.

Previous attempts have been made to reinforce this type of sweater by the attachment of inelastic reinforcing tapes along the interior of the shoulder lines 14, such tapes have readily broken away from their anchorages when stretching strains have been imposed on the body. In accordance with the present invention I solve the problem of preventing sagging or ripping of the garment at or

adjacent the shoulder lines by the provision of a piece of reinforcing material 16 preferably knitted and best seen in Fig. 2. This strip includes a substantially straight lower edge 17 extending from one armhole of the garment to the other, and at its upper edge is attached to the band 13 between the two shoulder lines 14. The member 16 tapers towards its ends, following and being connected to the shoulder lines 14 throughout their full length. The wales of the member 16 run longitudinally thereof, or in other words, at right angles to the direction of the wales of the garment body along the shoulder line. Thus, while the member 16 is free to stretch longitudinally to a certain extent, between its anchored ends 14, 14, it limits the stretching of the body across the shoulder line, and prevents stretching of the body to an extent which might rip the seams at 14.

The use of the member 16 prevents sagging in a manner which will be immediately apparent, and also prevents tearing of the garment along the seams 14 under any ordinary strain to which the garment may be subjected.

While not primarily intended for such use, the member 16 may also serve as a hanger upon which the sweater may be suspended from a hook when not in use. It is quite a common practice, even though these garments be provided with hanger straps, to suspend the sweater directly by the body thereof, with the result that the hooks frequently penetrate the body and spoil the appearance of the garment.

For practical purposes, it is advisable to attach the upper edge of the member 16 to the strip 13 between the upper or inner terminals of the shoulder lines 14. From a

strictly mechanical standpoint, in so far as the functioning of the strip 16 to prevent sagging is concerned, the strip might be connected to the sweater only along the shoulder lines, as it will be apparent that substantially all of the strain is transmitted directly to the anchored tapering ends of the strip rather than to its upper edge.

Various changes and alterations might be made in the general form and arrangement of the parts described without departing from the spirit and scope of the appended claim. Hence I do not wish to limit myself to the details set forth, but shall consider myself at liberty to make such changes and alterations as fairly fall within the spirit and scope of the appended claim.

I claim:

As a new article of manufacture a knitted coat sweater including a body and sleeves, a marginal band attached to the body, the ends of which lie along the adjacent front edges of the body and the intermediate portion of which defines the neck of the garment, a removable narrow yoke piece of sag resisting reinforcing material including a straight free lower edge extending from armhole to armhole within the garment, the upper edge of the intermediate portion of the yoke lying substantially parallel with its lower edge and being attached to that portion of the band lying between the ends of the shoulder line of the sweater, the ends of said upper edge being inclined downwardly relatively to the lower edge and coincident with and attached to the shoulder lines of the garment, the relatively narrow ends of the yoke itself being connected to the sleeves at the armholes.

JACOB ZIMMERMAN.
